CLAIM

The ornamental design for a telephone set, as shown and described.

DESCRIPTION

FIG. 1 is a top plan view of a telephone set showing my new design,

FIG. 2 is a bottom plan view thereof,

FIG. 3 is a right side elevation view thereof,

FIG. 4 is a left side elevation view thereof,

FIG. 5 is a front elevation view thereof; and,

FIG. 6 is a rear elevation view thereof.

The handset and cord has been omitted from FIGS. 2, 3 and 6; and the cord has been omitted from FIG. 5 for convenience of illustration.
